Primary Examiner — Kelley A Donnelly*(74) Attorney, Agent, or Firm* — Sterne, Kessler, Goldstein & Fox P.L.L.C.(57) **CLAIM**

The ornamental design for a retail display, as shown and described.

DESCRIPTION

FIG. 1 is a front view of a retail display showing the claimed design;

FIG. 2 is a top front perspective view thereof;

FIG. 3 is a bottom front perspective view thereof;

FIG. 4 is an enlarged view of the portion of FIG. 1 within dot-dash lines;

FIG. 5 is an enlarged view of the portion of FIG. 2 within dot-dash lines; and,

FIG. 6 is an enlarged view of the portion of FIG. 3 within dot-dash lines.

The dashed broken lines in the figures show portions of the retail display or environment that form no part of the claimed design.

The dot-dash broken lines in the figures show boundaries that form no part of the claimed design.

The Figures are illustrated to show contrasting appearance. Areas of the retail display that appear in different shades of gray represent areas with contrasting appearances.
